(57) **CLAIM**

The ornamental design for a portion of portable telephone, as shown.

DESCRIPTION

FIG. 1 is a front, top and right side perspective view of a portion of portable telephone, showing our new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a left side elevational view thereof;
 FIG. 7 is a right side elevational view thereof;
 FIG. 8 is an enlarged cross-sectional view thereof, taken along line 8—8 of FIG. 2, with the internal system omitted; and,
 FIG. 9 is a front, top and right side perspective view with the front cover opened thereof.

The broken line showing of a telephone handset throughout the views is for illustrative purposes only and forms no part of the claimed design.
